EXERCISE APPARATUS

Charles Robert Margolies, Oreland, Pa., assignor to Snyder Manufacturing Company, Philadelphia, Pa.,
a corporation of Pennsylvania

Filed Aug. 2, 1967, Ser. No. 8,117

Term of patent 7 years

(Cl. D34—5)

FIG. 3.

FIG. 2.

FIG. 4.

FIG. 1 is a perspective view of the exercise apparatus embodying my new design;

FIG. 2 is a side elevational view;

FIG. 3 is a top plan view;

FIG. 4 is a bottom plan view;

FIG. 5 is an end elevational view of the exerciser as viewed from the lefthand end of the apparatus shown in FIG. 2; and

FIG. 6 is an end elevational view of the exerciser as viewed from the righthand end in FIG. 2.

I claim:

The ornamental design of an exercise apparatus, substantially as shown and described.
